UNITED STATES PATENT OFFICE.

ALLEN C. MURDOCK, OF INLET, NEW YORK, ASSIGNOR OF ONE-HALF TO GERALD A. KENWELL, OF INLET, NEW YORK.

CUSPIDOR.

1,074,521.

Specification of Letters Patent. Patented Sept. 30, 1913.

Application filed April 8, 1913. Serial No. 759,735.

To all whom it may concern:

Be it known that I, ALLEN C. MURDOCK, a citizen of the United States, residing at Inlet, in the county of Hamilton and State of New York, have invented new and useful Improvements in Cuspidors, of which the following is a specification.

The invention relates to cuspidors and has for an object to provide a cuspidor particularly adapted for use on vehicles such as railroad coaches, electric cars and other conveyances of a similar nature.

The invention embodies, more particularly, a cuspidor which is preferably arranged in the panels forming the inner walls of the car and which is normally held in a closed position, the said cuspidor being arranged so that it can be readily swung into an open position for use and further arranged with respect to a series of pipes or conduits carried by the vehicle and having their inlet ends adjacent the cuspidor and their outlet ends exteriorly of the vehicle so that the contents of the cuspidor will readily pass into the conduits and gravitate to the ground exteriorly of the conveyance or vehicle.

With this object in view the invention embodies a clean and sanitary cuspidor which, when not in use, will not be visible to the casual observer in the conveyance or vehicle, and which will not be exposed to the atmosphere of the conveyance when not in use.

In the further disclosure of the invention reference is to be had to the accompanying drawings, constituting a part of this specification, in which similar characters of reference denote corresponding parts in all the views, and in which:

Figure 1 is a fragmentary elevation of a vehicle, looking at a wall of the interior thereof, and showing a panel having my cuspidor supported thereon, the cuspidor being shown in front elevation and in closed position; Fig. 2 is a vertical sectional view taken on the line 2—2 in Fig. 1, the dotted lines indicating the open position of the cuspidor; and Fig. 3 is a horizontal sectional view taken on the line 3—3 in Fig. 1.

Referring more particularly to the views, I disclose a panel 10 forming a part of the inner wall of a car 11, the said panel being arranged between the usual seats of the car and provided with a rectangular opening 12,

the upper and lower walls of the opening forming edges 13 in the panel when the opening is made, with the said edges beveled as shown in the views.

A plurality of supporting members 14 are journaled in the walls 15 of the car 11, each of the said supporting members consisting of a stem 16 revoluble in the wall and an integral circular head 17 formed at one end of the stem, a receptacle 18 being interposed between the supporting members 14, with the heads 17 rigidly secured to the receptacle so that the receptacle will be swingingly supported on the walls 15, the said receptacle being open at both ends and having the front wall 19 thereof constituting a part of the panel 10 when the receptacle is in closed position. As mentioned heretofore, the edges 13 constituting the upper and lower walls of the opening 12 are beveled and similarly the upper and lower edges of the front wall of the receptacle 18 are beveled, so that the beveled edges of the front wall of the receptacle engaging the beveled edges of the panel will limit the closing movement of the receptacle, as shown, a plurality of springs 20 being arranged to encircle the stems of the supporting members 14, with the inner ends of the springs secured to the receptacle and the outer ends secured to the stems so that the said springs will tend to normally swing the receptacle into closed position. A plate 21 is preferably secured to the front wall 19 and when the operator presses on the plate 21 it will be apparent that the receptacle will swing into open position against the action of the springs 20 so that the upper open end of the receptacle will lie within the interior of the car, whereas the moment the pressure on the plate 21 is discontinued the action of the springs 20 will return the receptacle to closed position so that the same will lie in the rear of the panel 10 and the front wall of the receptacle 18 will form a part of the panel to close the opening 12 therein.

The rear wall 22 of the receptacle 18 is preferably inclined toward the lower end thereof so that the contents of the receptacle will readily gravitate into a pipe 23 secured in the rear of the panel 10 and immediately beneath the receptacle, the said pipe including a flared head 24 adapted to be engaged by the lower end of the receptacle when the 110

same is swung into open position to limit the opening movement of the receptacle in the same manner that the beveled edges of the panel 10 limit the closing movement of the receptacle.

It will now be apparent that when the receptacle is in normal and closed position it will not be visible to the persons seated in the car and will not be open to the atmosphere of the car, thus preventing any disagreeable odor from sputum or tobacco previously projected into the receptacle from permeating the atmosphere within the car or vehicle. Now when it is desired to use the 10 cuspidor described, pressure is exerted on the plate 21, thus swinging the upper end of the receptacle within the interior of the car so that the excretion can be readily projected into the receptacle, after which the 15 pressure on the plate is released and the springs 20 will then return the receptacle to closed position, while the matter received in the receptacle will gravitate therein and pass into the pipe 23, the lower end of the 20 said pipe being adapted to pass exteriorly of the car so that the matter received in the receptacle will flow exteriorly of the car to the ground.

It should be particularly noted that when 25 the receptacle 18 is swung into an open position the opening movement of the receptacle will be limited by the lower end of the receptacle engaging the flared head 24 of the pipe 23, and it should be further noted 30 that when the receptacle is in normal and closed position the main body of the receptacle will lie outside of the panels of the car, while at the same time the front wall of the receptacle will form a part of the panel 35 and at the same time limit the closing move- 40

ment of the receptacle with respect to the panel.

It will be understood that various slight changes can be made from the disclosures in the drawings without departing from the 45 spirit of the invention, and that the scope of the invention is defined by the appended claim.

Having thus described my invention, I 50 claim:

In a cuspidor for cars including an apertured panel supported on the walls thereof, a plurality of supporting members journaled on the walls of the car, a receptacle 55 swingingly supported on the said supporting members and interposed therebetween, the said receptacle including a front beveled wall adapted to engage beveled edges of the panel and constitute a portion of the panel when the receptacle is in closed position, 60 springs carried by the supporting members and engaging the receptacle to swing the receptacle from an open to a closed position and normally hold the receptacle in closed position, a conduit arranged beneath the 65 receptacle and in the rear of the said panel, and a flared head projecting upwardly from the conduit and adapted to be engaged by the receptacle to limit the opening swinging movement thereof, the front wall of the said 70 receptacle engaging the said panel to close the aperture therein and being adapted to limit the closing swinging movement of the receptacle.

In testimony whereof I affix my signature 75 in presence of two witnesses.

ALLEN C. MURDOCK.
